UNITED STATES PATENT OFFICE.

FRANK F. WEAR AND BERNARD M. ELY, OF CINCINNATI, OHIO, ASSIGNEES TO THE
ALVEY-FERGUSON COMPANY, OF CINCINNATI, OHIO, A CORPORATION OF OHIO.

DESIGN FOR A COFFEE-MILL CASING.

47,660.

Specification for Design.

Patented July 27, 1915.

Application filed November 14, 1914. Serial No. 872,258. Term of patent 14 years.

To all whom it may concern:

Be it known that we, FRANK F. WEAR and BERNARD M. ELY, both citizens of the United States, residing at Cincinnati, in the county of Hamilton and State of Ohio, have invented a new, original, and ornamental Design for a Coffee-Mill Casing, of which the following is a specification, reference being had to the accompanying drawing, forming part thereof.

The figure is a perspective view of a coffee mill showing our new design.

Copies of this patent may be obtained for five cents each, by addressing the "Commissioner of Patents, Washington, D. C."

We claim:

The ornamental design for a coffee mill casing, substantially as shown.

FRANK F. WEAR.
BERNARD M. ELY.
